(57) **CLAIM**

The ornamental design for a LED lamp, as shown and described.

DESCRIPTION

FIG. 1 is a perspective view of an LED lamp showing our new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view thereof taken along the lines VIII—VIII' in FIG. 6;

FIG. 9 is an enlarged cross-sectional view of a part thereof indicated by an arrow A in FIG. 8;

FIG. 10 is a cross-sectional view thereof taken along the lines X—X' in FIG. 9;

FIG. 11 is an enlarged cross-sectional view of a part thereof indicated by an arrow B in FIG. 8; and,

FIG. 12 is an illustrative cross-sectional view showing the LED lamp according to our new design in use, the LED lamp being connected to another lamp and held unitarily by a holder shown in broken lines.
